UNITED STATES PATENT OFFICE.

JOHN Y. SAILOR, OF TIFFIN, OHIO.

FOLDING CRADLE.

SPECIFICATION forming part of Letters Patent No. 254,241, dated February 28, 1882.

Application filed September 17, 1881. (No model.)

To all whom it may concern:

Be it known that I, JOHN Y. SAILOR, a citizen of the United States, residing at Tiffin, in the county of Seneca and State of Ohio, have 5 invented a new Folding Cradle, of which the following is a specification.

My invention relates to improvements in folding cradles; and the objects of my improvements are, first, by folding when not in use to 10 take up less space than any others known to me; second, to place the cradle in a compact form, making it very convenient for shipping and storing. I attain these objects by the mechanism illustrated in the accompanying 15 drawings, in which—

Figure 1 is a perspective view of my cradle. Fig. 2 is the end elevation of the cradle closed. Fig. 3 is a side view of the center under round of the cradle. Fig. 4 is one of the legs with its 20 pivotal portion detached. Fig. 5 is the pivotal end of the leg shown at Fig. 4. Fig. 6 is a view of the several buttons.

Similar letters refer to similar parts throughout the several views.

25 The lock-boards A keep the several parts in position when open or closed. The arms b b b b work on the same with screws, and the slots F constitute the lock. The braces c c c equalize the weight between the top and 30 bottom rounds, also brace them. The rails J, rounds G, and spindles H constitute the sides.

The buttons s s s s secure the arms b b b b b to the rounds G G G G, and other similar buttons, s x, form the head on each end of bottom center round, G x, Fig. 3, which works 35 in the slots F. The legs d d d d x cross at the slots F, and are there secured together by center under round, G x, Fig. 3, and buttons s x. The lower part of the right leg, d x, turns on a pivot (fully illustrated in Figs. 4 and 5) and 40 throws the rocker e under the cradle.

Referring to Figs. 4 and 5, m is the pivot, and when adjusted into mortise L the groove n revolves around the peg p, which holds the same 45 in place.

I am aware that prior to my invention folding cradles have been made; but I am not aware that any cradles were made with the folding combination as I herein set forth.

What I claim, and desire to secure by Letters Patent of the United States, is—

The combination of lock-boards A, having slots F, cross-legs d d d d x, center under round, G x, and buttons s x, all substantially as and for the purpose shown and described.

JOHN Y. SAILOR.
